Letters Patent No. 84,403, dated November 24, 1868.

IMPROVEMENT IN PRINTING-PRESSES.

The Schedule referred to in these Letters Patent and making part of the same.

To all whom it may concern:

Be it known that I, SAMUEL J. BAIRD, of Staunton, in the county of Augusta, and State of Virginia, have invented a new and improved Frisket, Applicable to Drum-Cylinder-Impression Printing-Presses; and I do hereby declare that the following is a full and exact description thereof, reference being had to the accompanying drawings, and to the letters of reference marked thereon.

In the ordinary bed-and-platen printing-press, the frisket is a stiff iron frame, covered with a sheet of paper pasted thereon, and so cut out as to allow the type to strike the face of the sheet that is to be printed, whilst the interposing frisket protects the margins and blanks from being soiled by contact with the inky chase and furniture. The structure of the drum-cylinder presses precludes the use of this kind of frisket, and they are therefore unfit for fine book-printing, because of the liability of the margin's being soiled.

My improvement consists in making the frisket-frame of flexible materials, in order that it may be so bent, as it moves, as to avoid the ink-rollers, thus rendering it applicable to every variety of impression-cylinder presses.

To enable others skilled in the art to make and use my invention, I proceed to describe its construction and operation.

Figure 1 is a transverse section of so much of the machinery as is necessary to illustrate it.

Figure 2 is a plan view of the frame and bed of the press, the impression-cylinder and inking-rollers being removed.

Figure 3 is a vertical cross-section on the line *y y* of fig. 2.

In fig. 1, *A* represents the impression-cylinder resting upon the form *C*, which is supported and moved over the frame of the press, upon the friction-rollers *G G G*. *I* represents the frisket, with its bands, *J J'*, extending from *K* over the surface of the form, under the pulley *E*, and under the pulley *E'*, to the forward end of the bed at *K'*.

The sides of the frisket-frame may be made of cords, leather, chains, or other flexible substance, encased, if the nature of the material require it, in cloth, leather, or any suitable material. From it a border should extend inwardly, to which the frisket-sheet may be pasted. The ends of the frame may be of the same material as the sides, or they may be made of iron or other metal, as in the ordinary frisket.

The frisket is to be fastened to the press-bed at the rear end, by suitable hooks or hinges, at *K*. To the corners of the other end of the frisket, bands of leather or other suitable material are to be attached. These being drawn tightly over the pulley *F*, and under the pulley *E'*, are to be fastened to the forward end of the bed at *K'*.

When, therefore, the bed of the press is run out, it carries forward with it the frisket-bands, by reason of their fastening at *K'*. As the bands pass over the pulleys *F*, they draw in that direction the frisket, which passes under the pulleys *E*, and ascends between the impression-cylinder and the ink-rollers *D*, thus leaving the form until it has received the ink, when, the action

being reversed, it again descends upon it, as it returns under the impression-cylinder.

Instead of the frisket-bands being attached to the forward end of the bed at *K'*, as seen in the drawings, they may be carried upon pulleys over the impression-cylinder, and fastened to the rear end of the bed, or they may be carried over pulleys suitably located, and their motion be controlled by weights attached to their extremities.

Instead of the shield *S*, a roller, *S²*, fig. 2, may be used, either smooth or grooved, by means of which the frisket may be protected from contact with the ink-rollers, and the movement of the frisket-sheet more effectually directed, as its successive edges present themselves, and turn upward around the pulleys and shaft *c*, the motion of the roller being governed by the pressure of the thick sides of the frisket-frame as they pass between it and the pulleys *E E'*.

In addition to the firm latitudinal extension secured to the flexible frisket, by its tension on the pulleys, an additional arrangement may be adopted. It is illustrated in fig. 2. *H H H H* is the bed of the press, with the form, *C*, upon it. *K K'* are strips of wood or metal, of the thickness of the chase, extending from end to end of the bed, to which they are firmly fastened. On the upper surface of these strips are grooves, of proper size and form to receive the outer edges of the frisket-frame, which are to be corded or made thick, in order to fill the grooves. *d d* are slats or pieces, fastened to the frame of the press, on a line with the grooved pieces, and extending from the rear of the bed to the line of contact between the impression-cylinder and the form. These pieces occupy such a position as to cover the grooves when the bed of the press is run in, thus pressing the thickened edges of the frisket-frame into the grooves, and holding them firmly in place, whilst the frisket-sheet passes freely between the edges of the grooved pieces and the covering-strips. *L L* are frame-pieces, by which the covering-strips may be fastened to the frame of the press, or they may be fastened immediately to the sides of the frame, the grooves being correspondingly located.

The other parts of the press, being old, well known, and different in the different kinds of presses, are not here particularly described.

What I claim, and desire to secure by Letters Patent, is—

1. A flexible frisket, to be used in combination with a flat-form and cylinder-impression press, substantially as and for the purposes set forth.

2. The roller, smooth or grooved, for protecting the frisket from the ink-rollers, and directing its ascent, as above described.

2. The grooved frame above described, whether fixed or made movable, so as to be adjusted to any desired breadth of frisket, holding it firmly extended, as above described, and for the purposes specified.
